UNITED STATES PATENT OFFICE.

JAMES B. ATWOOD AND ALBERT W. SLATE, OF SPRINGFIELD, MASS.,
ASSIGNORS OF ONE-THIRD TO GEORGE DWIGHT, JR., OF SAME PLACE.

GAGE-COCK.

SPECIFICATION forming part of Letters Patent No. 310,490, dated January 6, 1885.

Application filed February 16, 1884. (No model.)

To all whom it may concern:

Be it known that we, JAMES B. ATWOOD and ALBERT W. SLATE, citizens of the United States, residing at Springfield, in the county 5 of Hampden and State of Massachusetts, have invented new and useful Improvements in Gage-Cocks, of which the following is a specification.

This invention relates to improvements in 10 gage-cocks and other valves intended to be directly connected to a steam-boiler by having a part thereof pass through the shell of the latter, the object being to provide gage-cocks and valves adapted for such connection with boilers in which the valve-closing parts are within 15 the boiler and open against the steam-pressure, and which are adapted to prevent the dangerous escape of steam into the cab of a locomotive when, owing to accident, the projecting 20 part of the gage-cock and valve-spindle are broken off.

In the drawings forming part of this specification, Figure 1 is a side elevation, and Fig. 2 a similar view, partly in section, of a gage-cock 25 embodying our invention. Fig. 3 is a section of the valve-spindle.

In the drawings, A is the valve-body, having 30 its rear end screw-threaded in the usual manner, to adapt it to be screwed into the boiler-shell B, and is provided with the usual discharge-nozzle, x. The valve-body is provided 35 with a longitudinally-central valve-stem passage, and has a bevel-edged valve-seat formed in its rear end around the end of said passage. The forward end of the body A is screwed to 40 provide for the reception thereon of the set-nut c and the stuffing-box nut b.

Between the part of the body A nearest the 45 outside of the boiler and that part thereof which is screwed into the latter is formed an annular groove, v, around the body, cut sufficiently deep to cause the metal between the base of the groove and the spindle-passage through the body to be of less thickness than any other part of the body, so that when the cock or valve is struck or forced laterally it

will break off, if at all, at the point where the body is made thin and weak, as at the groove v. The spindle d is provided with a conical-shaped valve, d', on its rear end, which 50 seats against the end of the body A within the boiler, and that part of the spindle between the valve d' and the nozzle x of the body is grooved longitudinally, so that steam and water may have a free passage from within the 55 boiler along the spindle to the nozzle. A groove, z, is made around the spindle d, to facilitate the discharge of water through the nozzle as the groove z is brought wholly or partly opposite the latter when the valve is 60 opened. The spindle d is made with an annular groove, w, around it opposite the groove v in the body, so as to weaken it at that point, and should the body be broken off, as above 65 described, to also cause the spindle to break off at the same time. Thus it will be seen that if the body A and spindle d be broken 70 off while steam-pressure is on the boiler, the screwed part of the body in which is the valve-seat and the part of the spindle on which 75 is the valve d' remain in the boiler, and, as the steam-pressure holds the valve d' close against its seat, no steam can escape to burn and scald any one who may be near. The spindle d is provided with a thread, which operates in the tapped end of the stuffing-box b, and the latter incloses the usual packing, o, which is compressed around the spindle and prevents leaking. The stuffing-box can, while the steam is on the boiler, be turned 80 off from the end of the body A, for the purpose of repacking the spindle, without permitting any steam to escape, and when the box is replaced; as in Fig. 1, the set-nut c is screwed against the end of it, to prevent it 85 from being jarred off. A wheel, e, is placed on the end of the spindle to turn the latter by.

It is obvious that substantially the construction herein shown and described may be adopted for any valve to be used for discharging steam from a boiler into a pipe, and for similar purposes, by adapting the end of

the nozzle x to have a leading-pipe screwed onto it.

What we claim as our invention is—

The body A of a gage-cock, having a longitudinal passage provided with a nozzle, cap, and packing, substantially as described, and having narrow annular groove v surrounding the same, in combination with the headed spindle d , having longitudinal grooves lead-

ing from the valve-seat to the escape-port, to and a circumferential groove, w , which is in line with groove v in the body when the valve is on its seat, substantially as described.

JAMES B. ATWOOD.

ALBERT W. SLATE.
